PROCESS FOR ELECTROLYTIC REDUCTION
OF PENTONIC ACID LACTONESHans Spiegelberg, Basel, Switzerland, assignor to
Hoffmann-La Roche Inc., Nutley, N. J., a corporation of New JerseyNo Drawing. Application January 18, 1946, Serial
No. 642,111. In Switzerland November 10, 1944Section 1, Public Law 690, August 8, 1946
Patent expires November 10, 1964

10 Claims. (Cl. 204—77)

1

Reduction of lactones of poly-hydroxy-carbonic acids to the corresponding sugars by means of sodium amalgam is a preparative method well-known in sugar-chemistry (see, for instance, Houben, "Die Methoden der organischen Chemie," 3rd edition, Vol. 3, page 240). The technical application of this method, however, meets with considerable difficulties, connected chiefly with the preparation and handling of great quantities of sodium amalgam. The mercury-vapours necessarily formed during the preparation of the amalgam from mercury and sodium disadvantageously affect the health of the workmen and the requirement of great quantities of mercury puts the profitability of the method in doubt. The troublesome manufacture of the amalgam by carrying sodium into the mercury, during which procedure the mercury is locally heated to high temperature by the vehement reaction accompanied by fire-phenomena, may be avoided by electrochemical preparation of the amalgam. However, this method, too, requires great quantities of mercury.

According to the present invention, lactones of poly-hydroxy-carbonic acids may be reduced at mercury-cathodes, if the electrolyte contains the salt of a metal apt to form an amalgam. The lactone is dissolved in a suitable catholyte in an electrolysis apparatus, the electrode rooms of which preferably are separated by a diaphragm (for instance made of clay). Aqueous solutions of alkali and zinc salts or of mixtures of these metals are especially suitable as electrolytes.

In the process according to the present invention, the electrolytically formed sodium amalgam acts as reducing agent. Consequent to the consumption of amalgam during the reduction a metal hydroxide, for instance alkali hydroxide when using alkali amalgam, is formed. Appropriately, the hydrogen-ion-concentration in the cathode room is kept substantially constant by continuous neutralisation of the base formed; this may, for instance, be effected by dropwise addition of acid into the cathode room. It is advisable to use for this neutralisation an acid containing the same anion as the salt employed for the preparation of the electrolyte; this causes the concentration of the electrolyte solution to remain substantially constant and the amalgam to be regenerated continuously. Since it has been found in practice that the quantity of acid needed for the neutralisation of the base is far lower than the quantity calculated from the electric current passed through the apparatus, it must be assumed that at least part of the hydrogen electrolytically

2

separating at the amalgam cathode takes part in the reduction of the lactone.

It is advantageous to effect the reduction, according to the present invention, in the presence of boric acid. The yields are thus higher and more equable and disadvantageous influences of impurities in the mercury are considerably reduced. It is recommendable to carry out the reaction at a temperature between +10 and +12° C.

10 According to the present invention high quantities of lactones may be reduced in equable high yields with comparatively small amounts of mercury, since a mercury layer of only a few millimetres height is sufficient for the formation of the cathode. It is a further advantage of the electrolytic method that one is free, according to the selection of the electrolyte, to select the amalgam or amalgam mixtures from a great variety of these substances. Thus, the reduction of lactones of poly-hydroxy-carbonic acids may, for instance, be effected at a sodium amalgam or potassium amalgam or a mixed potassium-sodium amalgam or sodium-zinc amalgam cathode.

Example 1

25 The electrolysis apparatus consists of a glass vessel at the bottom of which is the mercury cathode. The electric current is conducted to the cathode by a graphite rod placed in a glass tube in order to isolate the same against the catholyte. A clay cell which takes up the anolyte, is hung into the glass vessel in such a manner that the bottom of the cell is placed a few centimetres above the mercury cathode. A platinum wire-net covering the floor of the clay cell serves as anode. The catholyte is cooled by means of an enamelled iron worm. Speedy circulation of the catholyte between the floor of the clay cell and the mercury cathode is achieved by an effective stirrer.

30 A 15% aqueous sulphuric acid is poured into the clay cell while pure mercury and a solution of 600 parts by weight of crystallised sodium sulphate in 3000 parts of water are passed into the cathode room. In order to reach the appropriate concentration of amalgam, the sodium sulphate solution is first electrolysed alone for one hour with 40 amperes at a current density of about 20 amperes per dm.². After termination of this primary electrolysis, 300 parts by weight of ribolactone and 200 parts by weight of boric acid are added to the catholyte and electrolysis is continued with unchanged current density. The temperature of the catholyte should be below +12° C., preferably between +5 and +12° C. By dropping in dilute sulphuric acid, the solution is made weakly

acid to Congo paper (the said paper showing blue-greyish colour). The ribose content of the catholyte is measured from time to time by determination corresponding to Fehling. The maximum is reached within 4 to 4½ hours. Electrolysis is then broken off. For further batches no primary electrolysis is necessary, since the sodium content of the amalgam at the end of the first process is sufficient to start further electrolysis.

The isolation of the ribose from the electrolyte may, for instance, be effected as follows: The electrolyte is made weakly acid to litmus and then concentrated in vacuo to 1200 parts by volume at moderate temperature. Parts of the boric acid crystallise out and are separated by suction filtration. In the filtrate, the sodium sulphate is precipitated by addition of 2000 parts by volume of spirit and filtered off. The alcoholic ribose solution is concentrated to 2000 parts by volume, rendered alkaline to litmus by addition of sodium hydroxide and then again acidified by means of acetic acid. From this solution ribose is precipitated as the p-bromo-phenyl-hydrazone by stirring for 12 hours at room temperature with 250 parts by weight of p-bromo-phenyl-hydrazine. About 385 parts by weight of crude d-ribose-p-bromo-phenyl-hydrazone are obtained which after recrystallisation from absolute alcohol yield 360 parts by weight of the pure product melting at 167° C.

Ribose may be obtained from the ribose-p-bromo-phenyl-hydrazone by cleavage with benzaldehyde according to known methods (see, for instance, P. Karrer and coworkers, "Helvetica Chimica Acta," vol 18, 1935, p. 1445; and M. Steiger, "Helvetica Chimica Acta," vol. 19, 1936, p. 195).

Example 2

300 parts by weight of d-ribonic acid lactone are reduced at a potassium amalgam cathode in the apparatus described in Example 1. All working conditions are identical with those described in Example 1, with the exception of the catholyte containing, in place of 600 parts by weight of crystallised sodium sulphate, 250 parts by weight of potassium sulphate. Time wanted for electrolysis, working up and yield are as in Example 1.

Example 3

300 parts by weight of d-ribonic acid lactone are reduced at a potassium-sodium-amalgam electrode under the same conditions as given in Example 1. the catholyte, however, containing, in place of 600 parts by weight of sodium sulphate, a mixture of 300 parts by weight of crystallised sodium sulphate and 125 parts by weight of potassium sulphate. Time wanted for electrolysis, working up and yield are as in Example 1.

Example 4

300 parts by weight of d-ribo-lactone are reduced at a sodium-zinc-amalgam cathode under the conditions given in Example 1. Apart from the 600 parts by weight of crystallised sodium sulphate, 55 parts by weight of crystallised zinc sulphate are added to the catholyte. The determination according to Fehling shows that the maximum formation of ribose is reached already within 3½ hours, the said maximum, however, being somewhat lower than in Example 1. Accordingly, after working up as described in Example 1, the yield of d-ribose-p-bromo-phenyl-

hydrazone, amounting to 240 parts by weight, too, is somewhat lower.

Example 5

- 5 150 parts by weight of d-arabonic acid lactone
are reduced at a sodium-amalgam electrode in
the apparatus described in Example 1. The
catholyte consists of a solution of 300 parts by
weight of sodium sulphate in 1500 parts of water.
10 In order to form the amalgam cathode, this solution
is electrolysed during one hour at 20 amperes,
the cathode current density being 10 amperes per
dm.². After termination of this primary elec-
trolysis, 150 parts by weight of d-arabonic acid
15 lactone and 100 parts by weight of boric acid are
added to the sodium sulphate solution. Elec-
trolysis is continued for 5 hours at unchanged
current density. The temperature of the catho-
lyte is kept at about +12° C. by cooling, and
20 the pH is kept constant by dropwise addition of
sulphuric acid, as described in Example 1 (Congo
indicating paper should be greyish blue). For
isolating d-arabinose the electrolyte is carefully
25 concentrated in vacuo to 600 parts by volume.
Sodium sulphate is precipitated by adding 1000
parts by volume of spirit to the weakly Congo-
acid solution and separated off by suction filtra-
30 tion. After concentration of the filtrate to 1000
parts by volume, 140 parts by weight of diphenyl-
hydrazine-hydrochloride are added. Sodium
hydroxide is added while stirring until the solution
35 is alkaline, whereupon the latter is acidified
with acetic acid. After a short time, d-arabinose-
diphenyl-hydrazone precipitates. Precipitation
is completed by stirring for 12 hours, whereupon
the mixture is passed through a suction filter.
The crude diphenyl-hydrazone is washed suc-
cessively with n-ammonia, water, spirit and ben-
zene and then dried at 70° C. 162 parts by weight
40 of d-arabinose-diphenyl-hydrazone, having its
melting point at 216° C., are obtained, from
which d-arabinose may be obtained by cleavage
with formaldehyde or benzaldehyde by the
methods described by Neuberg and Wohlgemuth,
45 "Hoppe Seyler's Zeitschrift für physiologische
Chemie" vol. 35, year 1902, p. 34-36.

I claim:

  1. A process of reducing an inner lactone of a pentonic acid to a sugar which comprises sub-
jecting an aqueous electrolyte containing a salt
0 of a metal capable of forming an amalgam and
containing said lactone to electrolysis treatment
in an electrolysis cell, said reduction being effected
at an amalgam cathode in said cell, and main-
5 taining said electrolyte acid-responsive to Congo
indicator throughout said reduction of the lactone
to the sugar.
  2. A process according to claim 1 in which the
lactone is d-ribono-lactone.
  3. A process according to claim 1 in which the
lactone is d-arabono-lactone.
  4. A process according to claim 1 in which the
temperature throughout the reduction is main-
tained in the range of 5-12° C.
  5. A process according to claim 1 in which the
electrolytic solution contains a sulfate of an alkali
metal.
  6. A process according to claim 1 in which the
lactone is di-ribono-lactone, and in which the
0 electrolyte contains a sulfate of an alkali metal.
  7. A process according to claim 1 in which the
anodic zone is maintained separate from the
cathodic zone.
  8. A process of reducing an inner lactone of a
pentonic acid to a sugar which comprises sub-

jecting an aqueous electrolyte containing a salt of an alkali metal capable of forming an amalgam and containing said lactone to electrolysis treatment in an electrolysis cell, said reduction being effected at an amalgam cathode in said cell, and maintaining said electrolyte acid-responsive to Congo indicator throughout said reduction of the lactone to the sugar.

9. A process of reducing ribono-lactone to ribose which comprises subjecting an aqueous electrolyte containing a salt of a metal capable of forming an amalgam, boric acid, and also containing said lactone, to an electrolysis treatment in an electrolysis cell, said reduction being effected at an amalgam cathode in said cell, and maintaining said electrolyte acid-responsive to Congo indicator throughout said reduction of the lactone to ribose.

10. A process of reducing ribono-lactone to ribose which comprises subjecting an aqueous electrolyte containing a salt of an alkali metal capable of forming an amalgam, boric acid, and containing said lactone, to electrolysis treatment

in an electrolysis cell, said reduction being effected at an amalgam cathode in said cell, and maintaining said electrolyte acid-responsive to Congo indicator throughout said reduction of the lactone to ribose.

5 HANS SPIEGELBERG.
